UNITED STATES PATENT OFFICE.

CHARLES H. WHITAKER AND WALTER B. WHITAKER, OF DURHAM, NORTH CAROLINA.

MACHINE FOR DIPPING CIGARETTES.

SPECIFICATION forming part of Letters Patent No. 399,808, dated March 19, 1889.

Application filed June 13, 1888. Serial No. 276,925. (No model.)

To all whom it may concern:

Be it known that we, CHARLES H. WHITAKER and WALTER B. WHITAKER, citizens of the United States, residing at Durham, in the county of Durham and State of North Carolina, have invented a new and useful Improvement in Machines for Dipping Cigarettes, of which the following is a specification.

Our invention relates to an improvement in machines for dipping cigarettes; and it consists in the peculiar construction and combination of devices that will be more fully set forth hereinafter, and particularly pointed out in the claims.

15 In the accompanying drawings, Figure 1 is a side elevation of a cigarette-dipping machine embodying our improvement. Fig. 2 is a vertical longitudinal section of the same. Fig. 3 is a plan view of the same. Fig. 4 is a vertical transverse sectional view of the same, taken on the line *x x* of Fig. 1. Fig. 5 is a detail perspective view of the fingered drum, its shaft, and the gear-wheel and pulleys thereon. Fig. 6 is a detail view of the fingered drum and the disks.

25 A represents a vertical rectangular frame, at one end of which is a pair of inclined arms, B. In the upper ends of the said arms is journaled a shaft, C, which is provided at its center with a drum, D, and has a sprocket-wheel, E, at one end.

F represents a pair of vertical arms or standards which rise from the upper side of the frame A at a slight distance from the arms B, and in the said standards is journaled a shaft, G, which is provided with a drum, H, the latter being in line with the drum D and connected thereto by means of an endless conveyer, I. The said carrier is provided on its outer side with a series of transverse cleats, K, which are equidistant apart.

35 L represents a guideway, which is supported on vertical arms M, and has horizontal slides N in its sides, which are arranged in the same plane with the upper side of the conveyer I. The inner end of the guideway L is turned downward to form a mouth or discharge portion, O, and the inner ends of the slides N are also turned downward, as shown. A hopper

communicates with the said guideway to provide for a machine-feed for the conveyer I.

P represents a shaft, which is journaled in one end of the frame and is arranged under the guideway L. To the central portion of this shaft is secured a drum, R, and to one end thereof is secured a large sprocket-wheel, S, and a small sprocket-wheel, T. The latter is connected to the wheel E by means of an endless sprocket-chain. (Shown in dotted lines in Fig. 1.)

60 V represents a pair of vertical arms or standards, which have their lower ends rabbed in vertical grooves W in the sides of the frame. The lower ends of the said arms or standards are provided with vertical slots X, and clamping-bolts work in the said slots and engage the sides of the frame and serve to secure the arms or standards thereto at any desired vertical adjustment.

65 Y represents a shaft, which is journaled in the upper ends of the arms or standards and is provided with the drum Z.

A' represents an endless conveyer, which connects the drums Z and R, and is provided on its outer side with a series of transverse parallel buckets, B', which are independently secured to the carrier or conveyer A' and have semi-cylindrical or concave longitudinal recesses in their outer sides.

70 C' represents a guideway, which is arranged over the drum Z, and is supported by vertical arms or standards D'.

E' represents a shaft, which is journaled in the frame A in proximity to the standards V. In one end of the said shaft is secured a small sprocket-wheel, F', and at suitable distances from the center of the said shaft are secured a pair of circular disks, G'.

75 H' represents a shaft, which is journaled in the frame A at a suitable distance beyond the shaft E'. To the center of the said shaft H' is secured a drum, I', which is provided with a series of projecting peripheral fingers, K', the same being all curved in the direction in which the drum rotates. Secured to the said shaft H' near the drum I' is a pulley, L', which is of the same diameter as the said drum.

M' represents a sprocket-wheel, which is secured to one end of the shaft H', and is in line with the wheels F' and S, and N' and O' represent fast and loose pulleys, respectively, 5 which are on the opposite end of the shaft H'.

P' represents a pair of vertical arms or standards, which depend from the frame A, and have their upper ends rabbeted in vertical grooves R' in the sides of the frame. 10 The said upper ends of the standards are provided with vertical slots S', and clamping-bolts T' work in the said slots and engage the sides of the frame. The function of the said clamping-bolts is to secure the arms or standards at any desired vertical adjustment. 15

U' represents a shaft, which is journaled in the lower end of the standards or arms P', and is provided at one end with a small sprocket-wheel, V'. To the said shaft, near 20 the opposite end thereof, is secured a drum, W', the periphery of which is grooved, as shown, and an endless belt, X', connects the said drum and the pulley L' on shaft H'.

Y' represents a box or case, which is made 25 of sheet-iron or other suitable material, and is secured on one side of the frame A, near one end thereof. Arranged in the said box or case is a smaller box or case, A², a suitable space being formed between the opposing 30 sides of the said boxes or cases, and the said box or case A² has its upper side open, and is provided with a hinged door, B².

C² represents a steam-pipe, which communicates with a suitable boiler (not shown) 35 or other source of steam, and has its inner end secured in an opening in one end of the box or case Y', and communicating with the confined space therein, the function of the said pipe being to introduce steam to 40 the space which surrounds the box or case A², so as to heat the latter and thereby melt paraffine, which is placed therein. The pipe C² has a stop-cock or valve, D², by means of which the supply of steam may be controlled 45 or cut off.

E² represents a feed box or trough, which is arranged within a somewhat larger box, I², so as to form a steam-space between the said boxes, and the same are supported below 50 the frame A by means of depending arms or standards G². The said boxes or troughs are at such an elevation that the lower side of the drum W', and consequently of the endless belt X', are within the feed-trough, 55 so that paraffine, which is fed to the latter from the reservoir box or case A² by means of a pipe, H², will be supplied to the said endless belt when the machine is in operation. A steam-pipe, H², leads from the steam-space 60 of the reservoir-box A² to the steam-space surrounding the feed trough or box. The function of the said pipe is to introduce steam to the said steam-space, so as to maintain the paraffine in the feed-trough in a 65 melted condition. Depending from the steam-space, between the feed-trough and this in-

closing case F², is an escape-pipe, K², which is provided with a suitable stop-cock, whereby the escape of steam and water resulting from condensation may be regulated at will. 70

L² represents a pair of vertical arms or standards which depend from the frame A, and have their upper ends rabbeted in vertical grooves M² in the sides of the said frame, and said standards or arms have their upper ends provided further with vertical slots N². 75

O² represents clamping-bolts, which extend through the said slots and through the sides of the frame, the function of the said bolts being to secure the standards or arms at any 80 desired vertical adjustment. In the lower ends of said standards or arms is journaled a shaft, P², to the center of which is secured a peripherally-grooved drum or pulley, R². 85

S² represents a pair of horizontal arms or brackets which project longitudinally from one end of the frame, have their inner end rabbeted in grooves in one pair of the supporting-legs of the frame, and provided with 90 longitudinal slots T². Clamping-bolts U² work in the said slots and extend through the supporting-legs, and serve to secure the said bracket-arms at any desired longitudinal adjustment. In the outer ends of said arms is journaled a shaft, V², to the center of which is secured a drum or pulley, W², 95 which is in line with the drum or pulley R².

X² represents a large sprocket-wheel which is secured to one end of the shaft V². 100

Y² represents an endless sprocket-chain which connects the wheels X² and S, engages the under side of the wheel V', engages the upper side of the wheels M' and F', and engages the lower side of an idle sprocket-wheel, Z', the function of which is to tighten the endless chain. 105

From the foregoing description it will be understood that when the driving-shaft H' is rotated in the direction indicated by the arrow in Fig. 1 the shafts V², U', E', and P will be all rotated in the same direction and at different rates of speed, according to the size of the sprocket-wheels on the said shafts. 110

A³ represents an endless belt or carrier 115 which connects the drums W² and R², and is provided on its outer side with a series of transverse holders, B³, which are arranged parallel with each other and have longitudinal concaved recesses in their outer sides. 120

C³ represents a delivery-table which is supported in an inclined position in the frame A, near one end thereof, the lower end of the said delivery-table having a transverse opening, D³, which is arranged above the belt or carrier A³, and the upper end of the said inclined delivery-table being provided with extending arms or fingers E³, which bear against one side of the drum I'. In the side of the inclined delivery-table which is proximate to the endless belt X' is a longitudinal groove or slot, F³. The sides of the delivery-table 125 130

are turned upward at right angles and bear against the outer sides of the drum I' and pulley L'.

Projecting from the lower side of the guide-way C', on opposite sides of the same, are a pair of extension plates or arms, G³, which form gages and bear against the outer sides of the drum I' and pulley L'.

H³ represents an endless chain which connects the wheel E and wheel T, thereby imparting the rotary motion of the shaft P to the shaft C, and consequently causing the conveyer I to move in the direction represented by the arrow in Fig. 3 when the machine is in motion.

The operation of our invention is as follows: The cigarettes are fed one by one, either by hand or by a suitable machine, onto the conveyer I, and are arranged parallel on the said conveyer between the cleats K. The said conveyer serves to deliver the cigarettes one by one into the holders B' on the conveyer A', and as the said conveyer moves in the direction indicated by the arrow the cigarettes thereon are deposited singly and in rapid succession onto the peripheries of the revolving disks G'. The said disks are arranged in proximity to one side of the drum I', as shown in Fig. 2, and the said drum being also in rotation in the same direction as the disks, the cigarettes are each momentarily supported between the drum and the disks, and are caused to rotate with one end in contact with the belt X'. Inasmuch as the said belt travels through the melted paraffine in the feed-trough, the paraffine is caused to adhere to the outer side of the belt, and consequently comes in contact with one end of each cigarette in succession, so that while the cigarette is being rapidly revolved a thin film of the paraffine is applied thereto and caused to effectually coat the cigarette, and to do the same more neatly than if the end of the cigarette were dipped into a vessel of melted paraffine, as is now the common method employed. When the cigarette has been caused to thus make a sufficient number of revolutions, one pair of the curved fingers K', which project from the periphery of the drum, comes in contact with the cigarette and causes the same to be carried over the drum and dropped upon the inclined table C³, down which the cigarette rolls, and from which it drops into one of the holders B³ of the conveyer A³. By reason of the slot or groove F³ in the table the end of the cigarette which is coated with paraffine is prevented from coming in contact with the table, and the said paraffine coating partially cools and becomes solidified while the cigarette is rolling down the table. The drum I', the conveyers, and the revolving disks G' are so timed that only one cigarette will be at any time revolved between the drum and the disks, the space between the pairs of curved fingers K' being such that one pair of fingers will remove one cigarette as soon as its end has been coated and before another cigarette is dropped by the conveyer A' between

the drum and the disks. The conveyer A³ serves to receive the cigarettes from the table C³ and to drop the same into a suitable receptacle, and the length of the conveyer is such that while the cigarettes are being carried by the same the paraffine becomes entirely cooled and solidified, thus preventing the cigarettes from sticking together when bunched after having been delivered by the machine.

Having thus described our invention, we claim—

1. The combination, in a machine for dipping cigarettes, of the revolving disks G', the revolving drum I', in proximity thereto having the peripheral fingers K', and means, substantially as set forth, to apply the paraffine to the cigarettes while the same is revolving in contact with the drum and disks.

2. The combination of the revolving disks, the revolving drum in proximity thereto, whereby a cigarette fed to said drum and disks will be positively rotated by frictional contact with their moving surfaces, the trough or vessel to contain melted paraffine, and the endless belt working on a pulley in the contents of the said trough or vessel and passing over a pulley at one end of the drum and in contact with the revolving cigarette, substantially as described.

3. The combination, in a machine for dipping cigarettes, of the revolving disks, the revolving drum in proximity thereto, means, substantially as set forth, to apply melted paraffine to the cigarettes while the same are in succession revolving in contact with the drum and disks, and the conveyer having the holders B', to deliver the cigarettes in succession between the disks and the drum, substantially as described.

4. The combination, in a cigarette-dipping machine, of the revolving disks, the drum in proximity thereto and having the fingers K', and the inclined delivery-table having its upper end in proximity to one side of the revolving drum, and means, substantially as set forth, to apply paraffine to the cigarette while the latter is revolving in contact with the drum and disks, substantially as described.

5. The combination, in a machine for dipping cigarettes, of the revolving drum I' and the revolving disks in proximity thereto, with the inclined delivery-table, the latter having its upper end arranged in proximity to the drum and being provided at one side with a groove or slot, F³, and the conveyer having the holders B', to deliver the cigarettes in succession between the disks and drum, substantially as described.

6. In a cigarette-machine, the combination of the paraffine trough or case having the surrounding case F², whereby a steam-space is formed between said trough and said case F², the steam-pipe communicating with said case, the drum or pulley having its lower side arranged in the trough, the revolving drum I', having the pulley L', the endless belt con-

necting said pulley with the pulley in the paraffine-trough, and the disks in proximity to one side of the drum and revolving in the same direction therewith, substantially as described.

7. The combination, with the disks and fingered drum arranged in proximity to each other and revolving in the same direction, of the conveyer having the holders B', to deliver the cigarettes in succession between the disks and drum, the inclined delivery-table having its upper end bearing against one side of the drum, and the endless belt or carrier A³, arranged below the lower end of the delivery-table, substantially as described.

8. The combination, in a machine for dipping cigarettes, of the disks and drum ar-

ranged in proximity to each other and revolving in the same direction, the pulley at one end of the drum, the paraffine-feeding belt 20 passing over said pulley, the conveyer A', and the guide C', to deliver the cigarettes from the conveyer between the disks and the drum, and the gage-plates G³ on opposite sides of the drum and pulley, substantially as described. 25

In testimony that we claim the foregoing as our own we have hereto affixed our signatures in presence of two witnesses.
